UNITED STATES PATENT OFFICE.

JAMES E. MARSHALL, OF CLEVELAND, OHIO, ASSIGNOR TO GENERAL ELECTRIC COMPANY, A CORPORATION OF NEW YORK.

SEALING-IN MACHINE.

Application filed April 24, 1922. Serial No. 556,294.

To all whom it may concern:

Be it known that I, JAMES E. MARSHALL, a citizen of the United States, residing at Cleveland, county of Cuyahoga, State of Ohio, have invented certain new and useful Improvements in Sealing-In Machines, of which the following is a specification.

My invention relates to sealing-in machines and more particularly to spindles therefor. In application Serial No. 485,846, filed on April 24, 1919, by Mitchell and White, which is assigned to the assignee of the present application, there is disclosed a sealing-in machine which is particularly adapted for the sealing-in of mounts in so-called tipless incandescent lamps. My invention is an improvement on that of Mitchell and White and possesses a number of features and advantages which will be apparent from the following description of an embodiment thereof.

In the drawing, Figure 1 is a partial plan view of a sealing-in machine embodying my invention; Figure 2 is a partial vertical section of a spindle forming part of the said machine; Fig. 3 is a horizontal section on the line 3-3 of Figure 2; Figure 4 is a perspective view of a cam-way.

The sealing-in machine of which my improved spindle forms a part, is of the same general type as that disclosed in the Mitchell and White application hereinbefore referred to and in Patent No. 1,011,523 of December 12, 1911, granted to A. Swan, and comprises the bed 10 having mounted thereon the rotatable frame 11 carrying the spindles 12. The sealing-in operation comprises a series of steps and each spindle is caused to travel from one position to another and to pause at each position so that the bulb and other parts will be submitted to each of the required operations.

The spindle, to which my invention relates, is shown in Figures 2 and 3 and is carried by the rotatable frame 11. This spindle comprises a support for the bulb 13 which includes a collar 14 in which the bulb is centered, and suitable standards 15. These are carried by a base 16 having extending downwardly therefrom the hollow shaft 17 which extends through a suitable journal 18 in the frame 11. The base 16 preferably rests on an anti-friction bearing 19 carried by the frame 11. The hollow shaft 17 has fastened to the lower end there-

of a pulley 20 by means of which rotation may be given to the bulb and mount at certain points in the travel of the spindle, said pulley being engaged by the belt 21 for this purpose. At certain stages the lamp parts are submitted to the action of flames directed by burners 22 and are rotated during such operation. This is in accordance with well-known practice.

The stem 23 having attached thereto the exhaust tube 24 is of the type disclosed in Mitchell and White application, Serial No. 283,801. As is well-known, the practice is to fuse the neck 25 of the bulb to the flange 26 of the stem. The surplus portion 27 of the bulb neck is melted and blown off. It is requisite to direct air against the fused portion of the neck slightly below the line of union between the stem flare and the bulb at this stage of the operation. At the same time it is requisite to preserve a passage from the interior of the bulb to the atmosphere in order to allow the escape of air, the volume of which has been increased by the heating, from the interior of the bulb.

As shown in the drawing, the stem rests upon a tubular mountpin 28 which receives the exhaust tube 24 and is aligned with the hollow shaft 29 which extends through the base 16 and is keyed to shaft 17 of the bulb support so that it provides an open passage extending entirely through the spindle. This is of advantage in two ways inasmuch as it allows the escape of the expanded air from the interior of the bulb to the atmosphere and at the same time allows any broken tubes to drop through to the outside without plugging up the passage. The lower end of the shaft 29 carries a flange 30 which engages a track 31 which is shown in detail in Figure 4. The shaft 29 is slidable vertically and its position is determined by the track which is provided with rollers 31' upon which the flange 30 rests during rotation of the shaft 29. The shaft 29 carries a chuck which comprises chuck members such as balls 32 which extend through the sides of the said shaft and serve to engage the sides of the exhaust tube 24. These balls are ordinarily held in position engaging said tube by the loose sleeve 33 which forces them in on account of its weight and shape. However, when the whole mount support drops, which occurs

when the gap 34 in the track is reached by

the flange 30, the sleeve 33 encounters the base 16 and is raised, thus allowing the balls 32 to fall back out of engagement with the tube 24. The drop of the mount support 5 is limited by a stop 35 which engages the top of the sleeve 33.

In order to provide an air blast to blow off the bulb neck, passages are provided along the exterior of shaft 29, which carries 10 the sleeve 36. The sleeve 37 carrying the chuck members provides passages 38 communicating with the aforesaid passages of shaft 29, and the mount pin 28 may be provided with a flange 39 spaced from the top 15 of the member 37 in order to furnish a proper directing means for the air blast. The air is directed into the aforesaid passages by means of the nozzles 40, which are carried by conduits 41 suitably supported 20 by the bed of the machine and located at the proper points in the travel of the spindle.

What I claim as new and desire to secure by Letters Patent of the United States, is:—

- 25 1. In an apparatus for sealing into a bulb a mount having an exhaust tube extending longitudinally therefrom, the combination of a support for said bulb and means for supporting said mount within said bulb
- 30 comprising a hollow shaft for receiving a portion of said exhaust tube and allowing unobstructed communication therethrough from said exhaust tube to the atmosphere.
- 35 2. In an apparatus for sealing into a bulb a mount having an exhaust tube extending longitudinally therefrom, the combination of a support for said bulb and means for supporting said mount within said bulb comprising a hollow shaft for receiving a portion of said exhaust tube and allowing unobstructed communication therethrough from said exhaust tube to the atmosphere, a passage external of said shaft and having an outlet below the said mount and means 40 for directing air into said passage.
- 45 3. In a spindle for a sealing-in machine, a mount support comprising a straight-through hollow shaft for receiving an exhaust tube extending from said mount, and

means for directing air outwardly from a point below said mount comprising a passage extending parallel with that of said shaft but separated therefrom.

4. In an apparatus for sealing into a bulb a mount having a tube extending longitudinally therefrom, the combination of a support for said bulb and means for supporting said mount within said bulb comprising a hollow shaft for receiving a portion of said tube, chuck members extending through the sides of said shaft to engage said tube and actuating means for said chuck members adapted to bring into or out of engagement with said exhaust tube as desired.

5. In an apparatus for sealing into a bulb a mount having a tube extending longitudinally therefrom, the combination of a support for said bulb and means for supporting said mount within said bulb comprising a hollow shaft member for receiving a portion of said tube, chuck members extending through the sides of said shaft and a sleeve engaging said chuck members and supported on the exterior of said shaft and adapted to be reciprocated to release said chuck members or to force them to grip said tube.

6. In an apparatus for sealing into a bulb a mount having a tube extending longitudinally therefrom, the combination with a means for supporting said bulb with its neck extending downwardly and vertically, and means for supporting said mount within said bulb comprising a vertically extending hollow shaft for receiving a portion of said tube, chuck members extending through the sides of said shaft to engage said tube, a sleeve engaging said chuck members loosely mounted on said shaft and means automatically engaging said sleeve at intervals to raise said sleeve and to cause said chuck members to recede from engagement with said tube.

In witness whereof, I have hereunto set my hand this 21 day of April 1922.

JAMES E. MARSHALL.
